CLAIM

The ornamental design for an armband with light sheath as shown and described.

DESCRIPTION

FIG. 1 is a first perspective view of an armband with light sheath, showing our new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a second perspective view thereof.

The shorter dashed broken lines depict stitching that forms no part of the claim. The longer dashed broken lines depict portions of the armband with light sheath and form no part of the claimed design.

1 Claim, 5 Drawing Sheets
